UNITED STATES PATENT OFFICE.

WILLARD E. SWIFT, OF WORCESTER, MASSACHUSETTS, ASSIGNOR TO UNITED STATES ENVELOPE MACHINE COMPANY, OF SPRINGFIELD, MASSACHUSETTS, A CORPORATION OF MAINE.

ENVELOP-MACHINE.

1,202,917.

Specification of Letters Patent.

Patented Oct. 31, 1916.

Application filed August 16, 1911. Serial No. 644,399.

To all whom it may concern:

Be it known that I, WILLARD E. SWIFT, a citizen of the United States, residing at Worcester, in the county of Worcester and 5 Commonwealth of Massachusetts, have invented a new and useful Improvement in Envelop-Machines, of which the following is a specification, accompanied by drawings forming a part of the same.

10 My present invention relates to certain improvements in a mechanism for manufacturing that class of envelopes commonly known as outlook envelopes, or envelopes having a window opening in the body of the 15 envelop covered by a transparent patch of paper.

My present invention relates to mechanism 20 for forming a window in an envelop blank comprising an opening in the body portion of the blank covered by a transparent patch or covering attached to the blank around the edges of the opening, and is particularly adapted to form the component part of an envelop machine designed to manufacture 25 envelopes from a continuous strip of paper and sometimes known as rotary envelop machines.

The objects of my invention are to enable 30 the patch to be applied to the blank in proper registration to cover the opening therein while the blank is in motion, thereby obviating the necessity of bringing the blank to a state of rest to receive a patch, which would materially reduce the production of the machine, also to provide means, in connection 35 with the envelop making machinery of a so called rotary machine for forming the window opening in the blank, gumming around the opening and applying a transparent patch to said gummed surface to cover the window opening, without impeding the operations of the envelop machine.

In the accompanying drawings and in the 40 following description of my present invention I have represented it as applied to that type of a rotary envelop machine described in United States Patent No. 893,042, issued to James West July 14, 1908, as affording a sufficient disclosure of the character of my 45 present invention and a convenient method of carrying the same into effect. I do not, however, confine myself to any specific con-

struction of a rotary envelop machine, as my invention is capable of being applied to any envelop machine adapted to manufacture envelopes from a continuous strip of paper to which a longitudinal movement is imparted through the machine.

The objects of my present invention are accomplished by applying to the continuous 55 strip of paper at a convenient period in its progress through the machine a cutting die for forming an opening in the body portion of the blank, a gumming mechanism for applying gum around the opening, with means 60 for severing a patch from a continuous strip of paper, and applying the patch to the gummed surface around the opening by means of a pair of rolls between which the 65 continuous strip of paper containing the envelop blanks and the severed patches are passed simultaneously, one of said rolls being provided with a gripping mechanism which seizes the severed patch and holds it in proper registration to be applied to the envelop blank until the blank and patch are 70 both carried into the bight of the rolls. The pressure of the rolls causes the firm adhesion 75 of the patch to the gummed blank.

In the accompanying drawings I have 80 shown a mechanism for accomplishing these objects as applied to the machine described in the aforesaid patent to James West. Many details in the mechanism hereinafter described as embodying my invention can be 85 materially changed or modified without departing from the spirit of my invention, which consists in its essential feature in rolling the envelop blank and transparent patch simultaneously between a pair of rolls by 90 which both the blank and the patch are made to travel at a uniform speed during the period that the patch is being applied to the blank by the pressure of the rolls.

The principal object of my invention, 95 therefore, consists in providing means for applying a patch to the opening of an envelop blank while the latter is moving continuously through the machine, and this object I accomplish according to my present invention by the employment of pressing members having rolling contact surfaces between which the blank and patch are passed together, one of said pressing members having

means for maintaining the patch in position to register with the opening in the blank in order to avoid interrupting the movement of the blank while the patch is being applied.

5 Figure 1 is a side elevation shown in sec-
tional view of so much of the cutting and
folding mechanism of the envelop machine
described in the aforesaid patent to James
West, No. 893,042, as is necessary to illustrate
10 the operation of the mechanism embodying
my invention which is shown in connection
with the West cutting and folding mecha-
nism. Fig. 2 is a plan view of the mecha-
15 nism for severing a patch from the end of a
continuous piece of transparent paper and
applying the severed patch to an envelop
blank. Figs. 3 and 4 are detailed views of
portions of the patch severing mechanism,
20 Fig. 3 is shown in sectional view on the line
3—3, Fig. 2, and Fig. 4 is a sectional view on
the line 4—4, Fig. 2. Figs. 5 and 6 are de-
tailed views of portions of the patch grip-
ping mechanism. Figs. 7 and 8 show respec-
25 tively side and sectional views of the die for
cutting an opening in the body portion of the
envelop blank. Fig. 9 is a plan view of an
envelop blank of the form adapted to be
made by the mechanism illustrated in the
drawings. Fig. 10 represents a folded en-
30 envelop made from the blank shown in Fig. 9.

Similar reference letters and figures refer to similar parts in the different views.

I have omitted from the drawings, for the sake of clearness, all that part of the mechanism of the West machine which is not directly concerned in the application of my invention thereto, and reference may be had to the aforesaid patent to James West No. 893,042, for a description of any parts not shown in the present drawings.

Referring to Fig. 1, 1 denotes a portion of the framework upon which the operative parts are mounted, and 2 represents a continuous strip of paper from which the envelop blanks are formed, taken from a coil, not shown. Portions 3, 4, 5 and 6 are removed from the edges of the continuous strip 2 to form a blank of the form shown in Fig. 9, by means of a cutting mechanism, comprising a roll 7, against the sharp corner of which a pressure roll 8 impinges, causing the strip to be severed as it passes between the roll 8 and the corners of the roll 7. Rotating in connection with the roll 7 is a roll 9 having a cutting die 10, shown in cross section in Fig. 1, in outline in Fig. 7, and in longitudinal section in Fig. 8. By means of the die 10 a piece is cut from the body portion of the envelop blank to form the opening 11, Fig. 9. From the cutting mechanism the continuous strip 2 passes upward between the rolls 12 and 13. The roll 13 has applied to its surface in proper position, two peripheral strips 14 adapted to apply gum to the edges 15, 15 of the end flaps. The roll 13

is also provided with a gumming pad 16 properly shaped to apply gum to the surface 17 around the opening 11, and also with another gumming pad 18 adapted to apply gum to the surface 19 upon the back flap of the envelop blank. These several gumming strips or pads project slightly from the surface of the roll 13 and take gum from a gumming roll 20 revolving in a gum box 21. As the envelop blanks in the continuous strip 2 successively pass the gumming rolls they will have gum applied to the surfaces 15, 17 and 19, Fig. 9. From the gumming mechanism the continuous strip passes around an idler roll 22 carried upon a swinging frame 23 to which a spring 24 is applied to provide a yielding pressure of the roll 22 against the continuous strip 2. From the idler roll 22 the continuous strip 2 passes between a roll 25 and a segmental roll 26. Coöperating with the segmental roll 26 is a segmental roll 27, all three of said rolls being geared together, so that the peripheries of the segmental rolls will contact during each revolution. The transparent paper for the patches is contained in a continuous strip 28 held in a coil 29. The transparent strip 28 is carried beneath a roll 30 journaled in vertical slots 31 and having its weight supported upon the transparent strip. From the roll 30 the transparent strip is conducted over a roll 32 and between two friction plates 33 and 34, from which its free end 35 hangs loosely in the open space between the segmental rolls 26 and 27, the end 35 extending slightly below a line joining the centers of the two segmental rolls. The segmental roll 26 carries at each end a gripping mechanism, that at one end being shown in detail in Fig. 5.

The gripping mechanism comprises a bar 36, capable of a radially sliding movement in a slot 37 in the head 38 of the segmental roll 26. Attached to the bar 36 is a blade 39 having a slight outward curve 40 near its tip, as shown in Fig. 5, and being bent at its end at right angles at 41, to project over the head 38. The blade 39 is capable of a sliding movement between the head 38 and a plate 42 attached to the head 38 by screws 43, Fig. 6. The bar 36 is pressed radially inward by a spring 44 and at the proper period is crowded outwardly by means of a fixed cam 45 attached to the framework of the machine. As the segmental roll 26 rotates the bar 36 will be carried around the periphery of the cam 45 in the direction of the arrow 46, Fig. 1. As the bent tip 41 of the blade 39 passes the hanging end 35 of the transparent strip it is drawn radially inward by the cam 45 acting against the bar 36. As the blade 39 is acted upon by the cam 45 the movement of the bent section 40 between the head 38 and the plate 42 crowds the tip 41 over the edge of the transparent 130

strip. This conjoint movement of the tips 41 at the opposite ends of the segmental roll 26 cause them to grip the opposite edges of the transparent strip against the segmental roll 26. When this is accomplished, the continued movement of the segmental roll 26 will draw down the transparent strip 28 between the friction plates 33, 34, winding it up upon the periphery of the segmental roll 26. The segmental roll 26 carries in a recess 47, Fig. 4, a serrated cutting blade 48, Fig. 2, capable of a radially sliding movement in the recess 47, allowing it to be pushed outward into a recess 49 in the segmental roll 26. Each end of the blade 48, Fig. 2, is carried in a sliding yoke 50. The yoke 50 is capable of a sliding movement over a fixed sleeve 51, forming the journal bearing for the shaft of the segmental roll 26. The yokes 50 are provided with a tailpiece 52 which contacts with a fixed cam 53 by which the yokes 50 and the connected sliding blade 48 are periodically pushed radially outward into the recess 49 of the segmental roll 27, causing the serrated edge of the blade 48 to sever the continuous strip of transparent paper at a point below the line connecting the centers of the segmental rolls 26 and 27, leaving its end 35 hanging as before in position to be again gripped and drawn forward by the rotation of the segmented roll 26.

After the yokes 50 and blade 48 have been pushed radially forward to sever the transparent strip they are retracted by a pair of blade springs 54, shown in plan view in Fig. 2, one being shown in Fig. 4. These blade springs are attached at one end to the segmental roll 26 and their opposite ends enter mortises in the blade 48. These springs are straightened as the blade 48 is pushed outward, and when released from the cam 53 the springs 54 resume their curved form to draw the blade 48 into the recess 47 of the segmental roll 26, the curvature of the springs being sufficient to accomplish this result. From the patch applying mechanism the continuous strip 2 passes to a mechanism for folding the end flaps and severing the strip into individual blanks, comprising the rolls 55 and 56 provided with tucking and folding blades, and a cutting roll 57 having a cutting blade 58 coöperating with a recess in the roll 56. Each individual blank is then transferred to mechanisms for completing the folding operations to form an envelop, such as is represented at A in Fig. 10.

The mechanisms for severing the continuous strip 2 and for folding the blanks forms no part of my present invention, the same having been fully described in the aforementioned patent to James West.

My present invention relates solely to that portion of the above described mechanism which is concerned in cutting the window

openings, applying gum around the openings, and in applying transparent patches to the openings of envelop blanks in a continuous strip of paper in that class of envelop machines in which the strip is moved continuously without requiring an interruption in the movement of the paper strip. The pieces cut from the blanks to form the window openings by the cutting die 10 are received into the hollow shaft 9, from which they may be withdrawn by any suitable suction device applied to the end 9a of the shaft, Fig. 7.

I claim,

1. In a machine of the class described, means for imparting a longitudinal movement to a continuous strip of paper having regularly spaced openings therethrough provided with margins of adhesive material, a pair of rolls for applying pressure to the opposite sides of said strip, and means carried by one of the rolls of said pair for engaging and moving a transparent patch between said pair of rolls simultaneously with the passage of an opening between said pair of rolls.

2. A mechanism for applying a transparent patch to cover an opening in an envelop blank forming part of a continuous strip, comprising a pair of rolls between which the continuous strip is passed, whereby pressure is applied to said strip, gripping mechanism carried by one of said rolls, means for presenting the end of a continuous strip of transparent paper to said gripping mechanism, means for severing the strip of transparent paper, and means for releasing said gripping mechanism after the severed patch has been carried into the bight of said rolls.

3. A mechanism for applying a transparent patch to an envelop blank, comprising means for forming openings in successively fed blanks, means for applying gum around said openings during the feeding of said blanks, a pair of rolls between which said blanks are successively passed, and means carried by one of said rolls for engaging and moving a transparent patch between said pair of rolls simultaneously with the passage of a blank having an opening between said pair of rolls.

4. A mechanism for applying a transparent patch to cover an opening in an envelop blank, comprising a pair of rolls between which the blank is passed, gripping mechanism carried by one of said rolls, means for presenting the end of a continuous strip of transparent paper to said gripping mechanism, means for severing the strip of transparent paper, and means for releasing said gripping mechanism after the severed patch has been carried into the bight of said rolls.

5. A mechanism for applying a transparent patch to cover an opening in an envelop blank, comprising means for applying gum

around the opening of said blank, pressing members having surfaces in rolling contact with the blank as it passes between them, and means carried by one of said pressing members for engaging a patch, and for maintaining said patch in predetermined position during its passage between said press-

ing members to cover the opening in said blank.

Dated this fourteenth day of August 1911, 10

WILLARD E. SWIFT.
